United States Patent Office.

JOHN M. GRISWOLD, OF AUBURNDALE, MASSACHUSETTS.

Letters Patent No. 92,441, dated July 13, 1869.

IMPROVED MOSQUITO-SCREEN.

The Schedule referred to in these Letters Patent and making part of the same.

To all to whom these presents shall come:

Be it known that I, JOHN M. GRISWOLD, of Auburndale, in the county of Middlesex, and Commonwealth of Massachusetts, have made an invention of a new and useful Mosquito-Screen; and do hereby declare the following to be a full, clear, and exact description thereof, due reference being had to the accompanying drawings, making part of this specification, and in which—

Figure 1 is a vertical section, and

Figure 2, an outside elevation of a window-frame containing my invention.

Figure 3 is a vertical and longitudinal section, exhibiting the grooves or studs, to be hereinafter explained.

The object of the invention comprising the subject-matter of this patent, is to produce a simple, economical, and effective screen to exclude mosquitoes and other insects from habitable dwellings or apartments, and one which shall not interfere with the ordinary working of the window-sashes or blinds, the device covered by my invention occupying no valuable space when in use, and when out of season is capable of being packed and stowed away in extremely small compass.

The invention consists in the adoption of two thin flat rectangular frames, composed of wood or other suitable material, such frames being covered with a proper screen or gauze of woven-wire cloth, and disposed within the window-frame, and between its outer surface and the outermost sash, or between such sash and the blinds with which the window may at the time be supplied, the movements of such frames past one another in a vertical plane being guided by studs and grooves, the former of which are affixed to the opposite outer edges of the frames, and the latter made within or applied to the outer guide of the window-sash, or the facings, as they are termed by builders, the whole being in manner and operating as herein-after explained.

In carrying out my invention, I utilize the vertical strips or facings of the window-frame, which form the outer sash; or, rather, I utilize the intervening space now occupied between the two opposite strips or facings, and compel them to perform the office of guides to the vertical movements of the screen.

In the drawings, to which allusion has before been made as accompanying this specification, A denotes a window-frame, of ordinary construction, and of which *a* is the upper bar, and *b* the window-seat, the vertical strips of wood which divide the frame into spaces for receiving the sashes, being shown at *c* and *d*, the latter being the outermost one.

In carrying out my invention, I affix to the inner or contiguous face or edge of each opposite strip *d*, a thin strip, *e*, of equal or less width than such strip

or facing, and I form, in the face of such strip *e*, two upright alternated channels or grooves, *f f*, as represented.

g h, in the drawings, denote two open thin rectangular frames, covered with gauze or other suitable material, for preventing the passage of insects, the width of these frames being of such extent as to fill the intervening area created by the presence of the facings *d d*, the aggregate height of the two frames being equal to the distance between the top bar *a* and the seat *b* of the window-frame, or in excess thereof to the extent of the lap of their contiguous bars; that is to say, each frame is to fill one-half of the entire opening of the window-frame, the combined depth of the frames being preferably less than that of the facing with which they are connected.

The lower bar of each frame *g* or *h* is to be provided with a bolt or other proper means of securely holding it at any desired altitude.

The outer edge of each frame *g* or *h* is provided with two or more studs, *i i*, which extend into the channels *f f*, the purpose of the guides and channels being to determine or insure the proper vertical movements of the frames.

The above description embodies the mechanical construction of the device constituting my present invention.

It will be evident to intelligent persons, that while such device serves, while occupying the entire area of the window-frame, to effectually exclude the entrance of insects, it will not interfere with the ordinary movement of the sashes and blinds.

It will also be apparent, that when not wanted for use, the frames *g h* may be stored away into very small compass.

The device is cheap, not liable to derangement, and easily and quickly applied and removed, and may be applied with equal advantage to door-ways or other apertures as to the windows.

Having thus described the nature of my invention, as well as its construction and operation,

What I believe to be novel and original with myself, as well as useful to the public, and desire to secure by Letters Patent, is as follows:

I claim, as an improved insect-screen or guard, the device above described, consisting of the two frames *g h*, covered with a suitable netting, when the same are provided with the studs *i i*, and combined with the channels *f f*, made within the facings *d d*, or independent strips secured thereto, the arrangement and operation of the whole being as before explained.

JOHN M. GRISWOLD.
